SURGICAL LAMP

Austin A. Overbury, West Orange, N. J.

Application December 10, 1934, Serial No. 756,756

6 Claims. (Cl. 128—23)

This invention relates to a device for illuminating the oral cavity of a person and more particularly to a dental or surgical lamp which is adapted to be maintained in a fixed position within the oral cavity or mouth of a patient while a dental or any other surgical operation is being performed within the said oral cavity.

It is one object of the invention to provide a means for supporting a source of light, such as an electric lamp, in a manner which will permit the lamp to be inserted within the mouth of a patient and to adequately but comfortably clamp the said supporting means to the person of a patient.

It is a further object to provide a clamping structure for use with a surgical lamp, which is adapted to be clamped to some convenient projecting portion within the interior of the oral cavity of a patient, such as the tooth or gum structure, and also to a portion of the outer facial section, as beneath the lower jaw or chin.

It is also an object to provide a surgical lamp supporting means and a clamping structure which is of generally improved construction, whereby the device will be simple, durable and inexpensive in construction, as well as convenient, practical and efficient in use.

With the foregoing and other objects in view which will appear as the description proceeds, the invention resides in the combination and arrangement of parts, and in the details of construction hereinafter described.

The preferred embodiment of the invention is illustrated in the accompanying drawing, where-

5 in:

Figure 1 is a side elevational view of the device constructed in accordance with the invention;

Figure 2 is a front view of the device, looking in the direction of the arrow 2 on Figure 1;

40 Figure 3 is an enlarged fragmentary sectional detail taken on the line 3—3 of Figure 2 with parts broken away;

Figure 4 is an enlarged sectional detail showing a jack prong and the conductor of a conduit connected therewith; and

Figure 5 is a modified detail showing a shield for an electric lamp mounted on the lamp socket.

A source of light and a mounting therefor, designated generally by the reference character 10 is pivotally supported on a supporting frame structure, designated generally by the reference character 11. Said supporting frame structure includes two vertically disposed rods 12 and 13 which are spaced apart as shown in Figure 2, and 55 have a bracket 14 bridged across the upper ends

thereof, also a stationary grip handle 15 bridged across the lower ends thereof. The bracket 14 may be secured to the rod ends in any desirable manner, but is preferably constructed so as to provide a supporting shelf portion 16 also a downwardly disposed lip or jaw 17.

A vertically movable clamp member 18 is slidably mounted on the rods 12—13 and preferably comprises a flat plate member having one end 19 bent inward and the other end 21 bent outward, 10 the said inwardly bent end being arranged to slide over the rods 12—13 while the outward end is formed to provide a suitable clamping surface. Another plate 22 is secured to the vertically movable clamp member and has a grip handle portion 15 formed thereon which is in substantially vertical alignment with the stationary grip handle 15 and is also arranged to slide over the rods 12—13. Springs 24—24 are arranged over each of the rods 12—13 and between the grip handles 15 and 23, to thereby provide a yieldable upward pressure upon the vertically movable clamping member 18. The extent of the upward movement of said clamping member 18 is limited by the abutment provided by the lower surface of the 25 bracket 14.

The source of light and its mounting 10, include an electric lamp 25 which has a screw threaded connection with a socket 26, a reflector 20, a sleeve 27 secured within a neck on said 30 socket and a forked member 28, which is adapted to support said sleeve 27. Said forked member is pivotally mounted on a stud 29 secured in the bracket 14 and is seated upon the flanged end 31 of a bushing 32, which bushing is situated around 35 the lower end of said stud 29. The sleeve 27 is secured within the forked member 28 by means of a collar 33, which collar is secured on an outwardly extending end of said sleeve and is fixed 40 against one side of the forked member 28, while the opposite side of the forked member is engaged by the neck of the socket 26.

Current is supplied to one terminal of the electric lamp through a conduit 34, one end of which conduit passes through the sleeve 27, as shown in 45 Figure 3, and has the end of the conductor portion thereof formed integrally with a contact button 35, said button being embedded within a central cavity in an insulating washer 36, within the lamp socket 26. The opposite end of said conduit 50 passes through a flexible cable 37, adjoining one end of the sleeve 27 and the upper end of the rod 12, then through a central opening or bore 38 in the rod 12. At the lower end of said rod, the conductor of said conduit is joined integrally with 55

a prong 39 projecting below the rod 12, but is insulated therefrom by means of an insulating sleeve 38, as shown in detail in Figure 4. Through a second prong member 41, which is joined directly with the rod 13, the current is grounded to the other terminal of the electric lamp.

A horizontally slideable clamping means is also provided, which cooperates with the stationary jaw 17 on the bracket 14, and comprises a flat strip 42, having an elongated slot 43 therein, which is engaged by the bushing 32. A washer 44 is also placed over said bushing 32 and is situated between the strip 42 and the shelf portion of the bracket 14 to provide a seat for said strip. One end of said strip is bent downward and curved somewhat to provide a jaw 45, which is adapted to cooperate with the jaw 17 on the bracket 14. The opposite end of said strip 42 is also bent downward and has a clearance opening 46 therein which is engaged by a pin 47 projecting outward from the bracket 14. The strip 42 is thus permitted to pass over the pin 47 and over the upper surface of the washer 44. By means of a spring 48, the strip is normally biased in a direction which will tend to move the jaw 45 toward the jaw 17, and the normal space between the two jaws is adjustably controlled by means of a nut 49, which is adapted to be screwed on a screw threaded outer end of said pin 47. Soft elastic covers 51—51 will preferably be placed over the jaws as shown in Figure 3.

In operation, the device will be gripped by the grip handles 15 and 23 to draw the vertically movable clamp member 18 downward with one hand, then the lamp portion will be inserted in the patient's mouth. The jaws 17 and 45, on the bracket 14 and strip 42 respectfully, are then pressed into a clamping position over a convenient portion of the tooth or gum structure of the patient, after which the outer end 21 of the vertically movable clamping member 18 is placed in clamped engagement with the outer lower jaw or chin of the patient. After plugging the prongs 39 and 41 into a current supply socket, to light the lamp, the support for said lamp is rotated about the stud 29 to direct the light rays upon the portion of the mouth which is to be treated.

It will thus be observed that the light having once been set in the desired position, will continue to remain in such position regardless of any movement of the patient's head, which feature has been found to produce a very advantageous condition when performing delicate operations on the mouth, throat, tonsils, teeth, etc.

The lamp will preferably be of the low voltage type which will not produce enough heat to cause discomfort to the patient but if it is desirable to use a lamp which produces a greater heat, a translucent shield 52 may be employed as shown in Figure 5. In this structure the shield may be mounted on the reflector 53 and arranged in a spaced relation to the lamp. Ventilating openings may also be provided as at 54 if desired.

It will be understood that the invention may be embodied in other specific forms without departing from the spirit or essential attributes thereof and it is therefore desired that the present embodiment be considered in all respects as illustrative and not restrictive, reference being had to the appended claims rather than to the foregoing description to indicate the scope of the invention.

Having thus described my invention, I claim:

1. In a device for illuminating the oral cavity of a person, a supporting frame structure includ-

ing vertically disposed members having a supporting bracket at the upper end thereof, a source of light carried by said bracket, a horizontally slideable clamp member cooperating with said bracket to provide a clamping structure for engaging a portion of the interior of the oral cavity of the person, and a vertically movable clamp member slidably mounted on said vertically disposed members which is adapted to engage the outer lower jaw portion of the person.

2. In a device for illuminating the oral cavity of a person, a supporting frame structure including vertically disposed members having a supporting bracket at the upper end thereof, a source of light rotatably mounted on said bracket, a yieldable horizontally slideable clamp member cooperating with said bracket, and a yieldable vertically movable clamp member slidably mounted on said vertically disposed members, whereby said frame structure is adapted to be clamped to a portion of the oral cavity and the outer lower jaw portion of the person.

3. In a device for illuminating the oral cavity of a person, a supporting frame structure including vertically disposed members having a supporting bracket portion at the upper end thereof, a horizontally slideable clamping member cooperating with said bracket to provide one clamping structure which is adapted to be clamped to a portion of the gum or tooth structure within the oral cavity, a source of light pivotally mounted on said bracket and adapted to project within the oral cavity, and a vertically movable clamping member supported by said vertically disposed members which is adapted to engage the outer lower jaw portion of a person.

4. In a device for illuminating the oral cavity of a person, a supporting frame structure including vertically disposed members having a supporting bracket portion at the upper end thereof, a pivotal mounting carried by said bracket, a source of light carried by said pivotal mounting, a spring biased horizontally movable clamping member, having a clamping jaw arranged in operative relation with said bracket to grip a convenient projection within the oral cavity, and a spring biased vertically movable clamping member arranged to engage a convenient portion of the person outside of the oral cavity.

5. In a device for illuminating the oral cavity of a person, a supporting frame structure including two vertically disposed rods having a bracket portion bridging the upper ends thereof, a pivotal mounting carried by said bracket, a source of light carried by said pivotal mounting, a horizontally slideable clamping member carried by said bracket, a clamping jaw provided on both the horizontally slideable clamping member and bracket portion respectively, means to bias the movable jaw of the horizontally slideable member toward the jaw on the bracket, adjustable means to limit the normal position of the movable jaw, a vertically slideable clamping member having one portion thereof in slideable engagement with the vertically disposed rods, and means to bias said vertically slideable clamping member in an upward direction.

6. In a device for illuminating the oral cavity of a person, a supporting frame structure including two vertically disposed rods having a bracket portion bridging the upper ends thereof, a pivotal mounting carried by said bracket, a source of light including a socket having an electric lamp therein and carried by said pivotal mounting, means to carry a source of current to said elec-

tric lamp including a prong provided at the lower end of one rod and insulated therefrom and a prong connected in conductive relation with the other rod, a conduit running through a bore in one of said rods and connected to the insulated prong at one end thereof and to said electric

lamp at the other end thereof, a horizontally slideable clamp member carried by said bracket, and a vertically slideable clamp member guided on said vertically disposed rods.
